UNITED STATES PATENT OFFICE.

GEORGE W. PACKER, OF ROCK FALLS, ILLINOIS, ASSIGNOR TO THE EMPIRE
MANUFACTURING COMPANY, OF KEOKUK, IOWA.

NAIL-MACHINE.

SPECIFICATION forming part of Letters Patent No. 448,585, dated March 17, 1891.

Application filed October 21, 1889. Serial No. 327,694. (No model.)

To all whom it may concern:

Be it known that I, GEORGE W. PACKER, a citizen of the United States, residing at Rock Falls, in the county of Whiteside and State of Illinois, have invented certain new and useful Improvements in Nail Machines; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

15 My invention has reference to improvements in machines for making nails; and it consists in novel mechanism for severing the nail from the nail-bar, transferring the nail-blank when severed to and within clamping 20 and forming jaws, forming the head of the nail while being thus held, and discharging the finished nail.

In my invention the nail-bar is fed by its own gravity vertically downward through the 25 top and at about the center of the machine. The nails are severed therefrom by each of two cutting jaws or knives, which oscillate lengthwise of the machine, alternately past the lower end of the nail-bar, each of said cutting-knives working against its co-relative 30 stationary cutting-knife, between which cutting forces the nail-bar is alternately interposed, immediately before the cutting, by a preceding oscillation of the jaws which carry 35 and guide the nail-bar. The cutting surfaces of the respective moving knives and that of their co-relative stationary knives are oblique in reverse, so as to alternate the diagonal of the cut of the bar, and thus 40 serve the proper shape of the lower end of the latter. This part of the process is substantially that described in Letters Patent of the United States No. 374,807, granted to me December 13, 1887, for improvements in nail- 45 cutting machines, and the advantage in this mode of cutting in different oblique lines at each oscillation of the nail-bar consists in the fact that it dispenses with the necessity of turning the bar at the cutting of each nail 50 therefrom.

My present machine is very compact, and

all of the movements therein have their origin in and are governed solely by a longitudinal oscillating knife-head, which carries said movable knives.

55 In the drawings, Figure 1 represents a perspective view of a machine embodying the invention. Fig. 2 represents a vertical longitudinal section of the complete machine on the line $x-x$ of Fig. 3. Fig. 3 represents a vertical 60 transverse section of the complete machine on the line $x-x$ of Fig. 2. Fig. 4 represents a perspective view of the top of the knife-head B and adjoined parts, the nail-bar-feeding jaws and frame A being detached. Fig. 5 comprises 65 respective perspective views of the knife-head B, nail-header frame N forming-jaw frame H, nail-bar-feeding jaws and frame 5, and nail-blank movers 19, with attached shaft 20, and oscillating shaft 21. Fig. 6 represents a detail 70 sectional view of the upper part on one side of the knife-head, with attachments thereto.

75 Referring to the accompanying drawings, A designates the casing or frame of the machine. (Shown entire in Fig. 1.)

At the front end of the machine is the transverse main or driving shaft C, journaled in bearings in the side of the casing and carrying a fly-wheel on one end and a pulley E 80 on the other end.

B designates a knife-bearing head consisting of a vertical body B^2 and a horizontal arm B' . The said head B stands longitudinally within the casing A, and is provided 85 with opposite lateral trunnions 11 near its angle, having centrally in their ends conical frustum-shaped bearing-recesses B^3 B^3 to receive the similarly-shaped points of the pivotal rods or pins J, Fig. 3, that are supported 90 in suitable bearings in the adjacent sides of the casing, which sides are thickened at the points where the openings are to give longer bearings to the pivotal pins. The body B^2 of the knife-bearing head stands centrally within the casing, and the end of the arm B' is connected by a suitable pitman D with a crank C' of the driving-shaft C. In Fig. 5 is shown a perspective view of said head and pitman connected. The rotation of the main shaft 100 evidently vibrates the knife-bearing head on the pivotal pins J longitudinally to the casing.

77, Figs. 2, 3, and 4, are knives secured in an axial recess X in the body B², extending from the top thereof, which knives project a slight distance out of said recess. The knives 5 stand, respectively, near the front and rear sides of the recess X.

Extending from the center of the top of the casing A is a vertical feedway F for the nail-bar G, hereinafter more fully described.

10 The lower end of the feedway opens into the top of the chamber 3, situated centrally in the top of the casing and having its front and rear sides converging to its lower end.

15 66 are knives lying in sockets in said sides and converging downward toward the knives 77, Fig. 2. The knives 66 may be adjusted farther inward by means of spindle-rod having threaded ends and nuts thereon, as shown in Fig. 2. The cutting-edges of said knives 20 66 are inward and incline laterally in opposite directions, but at equal angles, the edges of the respective co-operating knives 7 having similar lateral inclinations. The cutting-edges of the knives 7 are outward and each 25 one co-operates with a knife 6 on the opposite side, as apparent from Fig. 2.

The nail-bar G is much wider than it is thick, as can be seen by comparing Figs. 2 and 3, and the nails are cut transversely from 30 its lower end. The opposite inclination of the edges of the opposite knives, which alternately cut nail-blanks from the nail-bar is to avoid turning the bar after each blank is cut off.

35 F, Fig. 2, is the vertical feedway for the nail-bar G, formed centrally in the top of the frame A and extending into the chamber 3, and W is a short transverse oscillatory shaft journaled in the upper part of the casing A 40 and having an opening through it of equal transverse area to and aligned with said way and in effect forming part thereof. The nail-bar G passes down the way F and has its lower end resting on one or the other of the shelves 13, which have the outer vertical walls 14, Figs. 2 and 6. The said shelves are secured to slide-rods 17, having bearings in lugs 16, rising from the head B on each side of the knives 7. The wall 14 of each shelf 13 stands 45 vertically under the cutting-edge of the corresponding knife 6, when a nail-blank is to be cut off by said knife and the co-operating knife 7. This is effected by the fixed catch 26, secured to the frame A, the catch 25, formed on the outer end of the slide-rod 17, and the coiled spring 15, surrounding said rod between the outer lug 16 and the collar 18 on the rod. (See Fig. 2.) The nail-bar is moved alternately from one set of knives 67 50 to the other or from one shelf 13 to the other by the jaws 4, the lower parts, Fig. 2, of which bear against the sides of said bar, while the upper parts 55 of the connected jaws, Fig. 3, are bent laterally outward and upward and 55 mounted on the shaft W, so that the jaws oscillate therewith. The knives thus cut off a

blank on each side alternately, alternate blanks having their thicker ends in opposite directions on account of the described inclination of the edges of the knives and the 70 walls 14, forming with the edges of the adjacent lower knives clamps for the blanks till they are pushed off the shelves 14.

During the act of cutting off a blank the nail-bar is temporarily at rest. This and the 75 oscillation of the shaft W are effected by the following means: 8, Figs. 1 and 2, is an arm standing from one end of the shaft W, and 9 is a pitman connecting the end of said arm and the forming-jaw frame II, Figs. 3 and 5, 80 that is mounted and swings longitudinally on the knife-head or knife-bearing head B, the said frame being composed of two similar sections, each having a hollow hub H', that is mounted on a trunnion 1 of the knife-head. 85 When these sections are in place, they are secured together by bolts or otherwise. The forming-jaw frame is provided with the two forming-arms K, standing from opposite sides of the frame, Fig. 5, and inclined at equal 90 angles in the opposite directions, there being an arm on each section of the frame. The lower end of the pitman is attached to one of said arms by a bolt and nut 10, Figs. 3 and 5. As the frame II swings, the pitman and arm 8 95 cause the shaft W to oscillate. The upper end of the pitman 9, Figs. 1 and 2, is flattened and provided with a vertical slot 11, of suitable length, and a bolt 12 passes through said slot and engages in a threaded recess in the 100 arm 8, so that while the pitman is rising or falling the length of said slot the arm 8 is not moved nor the shaft W oscillated. This happens when the nail-bar is in position to be cut on either side. The bottoms of the shelves 105 13 are cut away to permit the blank-movers to act.

19 19, Figs. 2, 3, and 5, are the blank-movers, which have their lower ends mounted on the shaft 20 and stand in the recess X. The 110 said shaft is mounted in a long longitudinal bearing recess in the knife-head, Fig. 2, and has on its outer end an arm 21, provided with a stud 22, preferably carrying an anti-friction roller 24. The said anti-friction roller, Figs. 115 1 and 2, rests in an upright slot 23 in a bar crossing an opening in the rear of the casing. The ends of said slot are vertical; but its central portion is inclined, as shown in Fig. 1. Now as the shaft 20 partakes of the oscillation of the knife-head the anti-friction roller must move up and down in the slot and when passing the inclined portion thereof must slightly rotate the shaft, so that the blank-movers are alternately moved in opposite 120 directions thereby, and as the said movers fall in opposite directions and move the alternate blanks off the shelves from opposite sides one does its work when the knife-head is ascending and the other when said head is descending. From the movers 19 the blanks go to the 125 forming-jaws L L, seated in and carried by 130

the arms K of the frame H, which arms are, as seen fully in Fig. 4, on opposite sides of the casing and facing opposite ways.

Opposed to each jaw L is a jaw M, seated in and carried by the knife-head B and participating in the motion of said head. In the opposing faces of the jaws L M there are recesses to give the shank of the nail its proper formation.

15 As the parts that directly move the forming-jaw frame H, and consequently the jaws L, are themselves actuated by the mechanism that moves the header-frame, the latter frame and mechanism will be first described.

15 N, Figs. 2, 3, and 5, designates the header-frame or the frame carrying the heading-dies. The header-frame straddles the hollow hubs H' of the forming-jaw frame H, and is attached to the knife-head B at front and rear by the 20 pivotal pins N' passing through openings in the front and rear bosses of the header-frame and entering seats 27 in the front and rear of the upright part of the knife-head, the ends of the pins N' and said seats being conical, as 25 shown. For convenience the shaft 20 passes axially through the rear pin N'; but said pin and shaft have no common connection nor motion.

25 P P are cylindrical heading-dies, having 30 transverse seats in the upper part of the header-frame on opposite sides thereof and at suitable points not facing each other, as they coact with the jaws L M on opposite sides. (See Fig. 4.) Each heading-die is cylindrical and is so situated and arranged that its inner 35 end will be brought against the larger or thicker end of a nail-blank, held by the corresponding dies L M, as the header-frame oscillates laterally on the pins N' on the knife-head. This lateral oscillating is imparted to the header-frame by the following means: O 40 Figs. 1 and 3, are similar levers, each having spherical heads at its ends and situated on opposite sides of the casing of the machine. The construction and operation of said levers will be best understood by consulting Fig. 1. In said figure the lever O shown has a socket 45 28 for its lower head in a portion of the casing and extends thence upward and forward, its upper head having a similar socket 29 in the lower side of the socket or housing of the heading-die P on that side. The construction and arrangement of the opposite ball-and-socket lever O is the same, except that the latter lever inclines upward and rearward from its lower socket 28 to its upper socket 29. Now the header-frame must vibrate longitudinally with the knife-head B, to which it is attached, and, as the lower socket 28 is 55 fixed and the lever O is rigid, when the said frame is depressed rearward, Fig. 1, with the knife-head, as the latter vibrates rearward the said lever must turn the header-frame laterally inward on its pins N' N' and bring 60 the heading-die, as described, against the nail-blanks. When the knife-head reverses its movement, the opposite lever O, having an

opposite inclination, throws the header-frame inward from the opposite side, and so the heading-dies are caused to act alternately. 70

R R are ball-and-socket levers having their lower spherical heads seated in sockets in the front and rear bosses of the header-frames, Fig. 2, and their upper heads seated in similar sockets in the under side of the corresponding arm K of the forming-jaw frame. 75

In consequence of the situations of said arms the levers R must necessarily incline upward and outward laterally at equal but opposite angles. Now when the header-frame is turned 80 or rolled laterally inward by the lever O, (see Fig. 2,) the corresponding lever R would tend to be compressed longitudinally, and as it cannot relieve its tension by moving its lower socket and the bars of frame N it necessarily 85 moves the arm K longitudinally rearward, causing the forming or gripping die L to close on the nail-blank lying against the end of the corresponding die M. The parts are so arranged that this happens just before the 90 heading-die strikes the nail-blank to form the head. The action of the rear lever R is similar, but alternates with the action of the front lever. When the action has been completed and the jaws L M have let go, the finished 95 nails fall through the ways S S into suitable receptacles below. The nail-bar descends or is fed to and between the knives by gravity.

What I claim as my invention, and desire 100 to secure by Letters Patent of the United States, is—

1. In a nail-machine, the combination of a stationary knife 6, movable knife 7, a shelf 13, adapted to receive the nail-blank, and 105 mechanism, substantially as shown, for retaining said snell in position to receive the severed blank, for the purpose specified.

2. In a nail-machine, the combination of the oscillating knife-head B, provided with 110 knives 7 and forming and gripping jaws M, the stationary knives 6, the frame N, pivoted thereon, provided with dies P, and forming-jaw frame H, seated on the head B and provided with arms K and forming-dies L, the said 115 parts having substantially the inter-relation and coaction shown, whereby the nail-blank is severed, gripped laterally, and headed during each oscillation of the head B, substantially as shown and for the purpose described. 120

3. In a nail-machine, the knife-bearing head B, provided with the stationary die M, the frame H, pivotally seated on the head B and provided with the die-bearing arms K and dies L, the stationary knives 6, the frame 125 N, provided with the heading-dies P, shelf 13, and blank-movers 19, whereby the nail is severed and completed at each oscillation of the head B and the control of the nail-blank is retained from before its severance until after 130 its completion, substantially as shown, and for the purpose described.

4. In a nail-machine, the combination of a casing A, a knife-head B, adapted to oscillate

thereon, the frame N, pivoted centrally lengthwise of the head B, the oscillating levers O, forming-jaw frame II, pivotally seated on the head B, and the levers R, substantially as shown, and for the purpose described.

5. In a nail-machine, the combination of the casing A, oscillating head B, pivoted frame N, and levers O, seated in diagonal relation on opposite sides of said frame with their bases projected from the vertical line of oscillation and oppositely from the center of oscillation, substantially as shown, whereby is effected the lineal and lateral oscillation, for the purpose specified.

10 6. In a nail-machine, the combination of the blank-movers 19, shaft 20, arm 21, and slot 23, having its middle portion inclined, substantially as shown, and for the purpose described.

20 7. In a nail-machine, in combination with the shelf 13, adapted to receive the severed blank, a blank-moving device 19, adapted to enter and partially traverse its recess and remove said blank therefrom, substantially as shown, and for the purpose described.

25 8. In a nail-machine, the combination of the opposing cutting-knives 6 and 7, shelf 13, seated in relation to receive the severed blank therefrom, opposing jaws L and M, adapted to form an intervening interval in substantial prolongation of the shelf 13, and a blank-mover 19, adapted to carry the severed blank from said shelf to and within the grasp of the said forming-jaws, whereby constant control 30 of the blank is retained, substantially as shown, and for the purpose described.

35 9. In a nail-machine, the combination of a casing A, an oscillating head B, provided with trunnions 1, supporting centers or pins J, the main shaft having the crank C', the pitman connecting said head B and crank, frame N, centers N', and levers O, seated as described and adapted to laterally oscillate the frame N during the lineal oscillation of the latter, substantially as shown, and for the purpose described.

40 10. In a nail-machine, the combination of the oscillating frame II, pitman 9, pivoted thereto and provided with slot 11, oscillating

45 shaft W, provided with arm 8, and bolt 12, substantially as shown, and for the purpose described.

11. In a nail-machine, the combination of the oscillating head B, the blank-mover 19, shaft 20, arm 21, boss 22, and stationary slot 23, substantially as shown, and for the purpose described.

12. In a nail-machine, the combination of the shelf 13, adapted to receive the severed nail, forming-jaws L and M, and blank-mover 19, adapted to move the nail-blank endwise from said shelf to and between said jaws, substantially as shown, and for the purpose described.

13. In a nail-machine, the combination of the frame A, the oscillating head B, provided with forming-jaw M, the driving-crank shaft, the pitman connecting the said shaft and head B, the frame N, the levers O, the jaw-frame II, provided with forming-jaw I, and the levers R, substantially as shown, and for the purpose described.

14. In a nail-machine, the combination of a frame A, head B, pivotally seated thereon and provided with jaw M and knife 7, pitman D, actuating-shaft C, frame II, provided with 50 jaw L, levers O and R, shelf 13, springs 15, hooks 25 26, and stationary knife 6, substantially as shown, and for the purpose described.

15. In a nail-machine, the combination of the frame A, provided with vertical nail-bar 80 feed F and knives 6, hooks 26, and slot 23, axle C, pitman D, frame N, centers N', braces O, heading-dies P, head II, provided with jaw L, braces R, centers J, head B, provided with knives 7 and with retaining-recess 13 14, guiding-jaws 4, blank-movers 19, shaft 20, arm 21, and boss 22, all interarranged and operating substantially as shown, and for the purpose described.

90 In testimony whereof I affix my signature in presence of two witnesses.

GEORGE W. PACKER.
